UNITED STATES PATENT OFFICE.

ADOLPH F. YOUNG, OF CHARLEVOIX, MICHIGAN, ASSIGNOR TO EUREKA CARBURETER COMPANY, OF CHARLEVOIX, MICHIGAN, A CORPORATION OF MICHIGAN.

CARBURETER.

1,247,478.

Specification of Letters Patent. Patented Nov. 20, 1917.

Application filed March 2, 1917. Serial No. 152,044.

To all whom it may concern:

Be it known that I, ADOLPH F. YOUNG, a citizen of the United States, residing at Charlevoix, in the county of Charlevoix and 5 State of Michigan, have invented new and useful Improvements in Carbureters, of which the following is a specification.

This invention relates to means for controlling the supply of air and gasoline in proper proportions to meet the requirements 10 of the load and one feature of the invention pertains to a fuel valve arrangement by which the said valve is in initially open position for starting and is controlled, as to 15 its changes in position, by the varying suction or pull existing in the manifold, that is, at a point between the throttle valve and the engine, which suction tends to close said valve. An auxiliary air intake valve or 20 regulating member is also employed which is controlled by the said suction or pull existing in the manifold at the point stated, this suction, tending to close the auxiliary air intake valve and move the fuel valve 25 toward closed position and acting in opposition to the normal tendency of the air intake valve or regulating member and the fuel valve to remain open. This suction pull exerted upon the auxiliary air regulating 30 means and the fuel valve varies in degree inversely to the degree of open position of the throttle valve or the supply of air through the main air intake and it varies also during the running of the engine, ac- 35 cording to the load imposed thereon, the said controlling mechanism, comprising the auxiliary air and fuel valves, accommodating itself within certain limits to the requirements of the work being done.

40 The chief object of the present invention is to so arrange the auxiliary air conduit that it will take its supply of non-carbureted air from the main air passage in advance of the fuel valve and bypass said non-carbureted air to the suction connection beyond the throttle valve, combined with means for simultaneously choking or strangling both the main and auxiliary air supplies.

45 The invention consists in the features and 50 combination and arrangement of parts hereinafter described and particularly pointed out in the claims, and the invention is in the nature of an improvement upon the carbure-

reter set forth and described in a co-pending application of John Vodicka and A. F. 55 Young, filed Jan. 6, 1916, Serial No. 70,642, allowed Sept. 16, 1916.

In the drawings:

Figure 1 is a side elevation of the invention; 60

Fig. 2 is a vertical sectional view of the invention with parts in elevation;

Fig. 3 is a detail plan view, with parts in section;

Fig. 4 is a view of part of Fig. 1 a quarter 65 turn therefrom; and

Fig. 5 shows a vertical sectional view of a modification.

In these drawings, 1 indicates a fuel inlet, to which the oil is supplied in ordinary manner by a float controlled valve. 2 is the needle valve controlling the intake of fuel. This valve is surrounded by a well 2' containing oil. 3 is the main air inlet from which the air is directed past the fuel valve 75 to have an aspirating action in taking up and carrying along the fuel, 3' designating an air choke valve controlling said air inlet. 4 is the throttle valve, all these parts being located in a casing 5 in substantially 80 the well known manner. The manifold connection is represented at 6. The needle valve stem extends up through the well of the casing and is connected pivotally at a point 8, outside the same with a lever 7 fulcrumed at 9 between the collars or heads of a screw 10 mounted in the ear 11 on the cylinder 12. The other end of the lever 7 is pivotally connected to a link 13, the upper end of which is connected adjustably with 85 an arm or lever 14 pivoted at 15 in an ear or bracket 16 extending from the cylinder wall or frame, the said adjustable connection being formed by the pivot pin or screw 17 of the link passing through a slot 18 in 95 the lever, said pin or screw being held in any position to which it may be adjusted by a clamp nut 18'. The range of adjustment of the upper end of the link is such that in one position the pivot 17 of the link will 100 coincide substantially with the pivot 15 of the lever 14, but in other positions the connecting point will be at different distances from the pivot.

The lever 14 has a forked end engaging 105 under a headed pin or projection on a con-

troller member 19 in the form of a piston working in the cylinder, and pressed upwardly by a spring 20, this spring lifting the piston to open the fuel valve through 5 the lever 14, link 13 and lever 7 when the link is properly adjusted in the slot 18 to derive the desired degree of movement from the piston. This piston also serves as a valve for controlling the auxiliary air intake 10 21 communicating with the cylinder 12 and in communication with the inlet 3 and the manifold connection 6. The auxiliary air passes through the conduit, or pipe 21' to the manifold at a point between the throttle 15 valve and the engine, furnishing as it does an auxiliary air supply and also providing a suction connection beyond the throttle valve, through which the suction pull in the manifold will exert control upon the piston 20 19, which in turn controls the auxiliary air intake and the fuel valve.

The fuel valve is initially set in wide open position and for this purpose the lever 7 at its fulcrum is adjusted up or down by means 25 of the screw 10. Having adjusted this screw to determine the proper position of the valve, the spring in the piston chamber, acting on said piston 19, will maintain the fuel valve in its wide open position at first 30 for starting the engine and until such time as the suction pull overcomes the pressure of the spring and draws the piston downwardly.

By adjusting the link at its upper end 35 along the arm or lever 14, different degrees of movement may be imparted to the fuel valve through said link and the lever 7 from the movement of the piston, this adjustment determining the position of the fuel valve for 40 high speed, while the adjustment of the lever 7 determines the wide open position of the valve for low speed or starting. When the carburetor is properly adjusted, at no time will the needle valve be fully closed.

45 The operation is as follows:

We will suppose that the fuel valve operating lever 7 has been adjusted to determine the desired position of the fuel valve for starting or for low speed, and it is desired 50 to run the engine, at this time, while the engine is at rest, the spring in the piston chamber has raised the piston and the fuel valve is as wide open as the adjustment just mentioned will permit. The operator now opens 55 the throttle valve a little and upon cranking or starting the engine air will rush in through the main air intake and by its aspirating effect will carry along with it a supply of the fuel from the oil well 2' at the 60 valve which at first is wide open.

This rich mixture will flow past the throttle valve and into the manifold and engine to furnish the supply for the first explosion in starting the engine. This same suction 65 action will become effective on the piston in

the controlling chamber and will draw the same down and cut off the inlet of air through the auxiliary air port and it will also partly close the fuel inlet valve, and so long as the throttle valve is held in this position, i. e. opened a little way from running at a low speed, the parts will remain substantially in this position, the air being drawn in through the main intake only past the fuel valve and forming therewith the desired mixture to be delivered to the engine. The cutting off of the auxiliary air prevents the mixture from being thinned or rendered lean at this time.

When the speed is to be increased or the engine is to carry a greater load, the throttle valve is opened wider and consequently the air entering the main intake meeting less obstruction to its free passage for supplying the vacuum created by the suction, will flow in the main air intake in greater volume, thereby reducing the suction action on the piston 19 and allowing the spring to raise the piston and partially or fully open the auxiliary air intake in accordance with the working of the engine and also the fuel valve, so that more fuel will be supplied and also more air, that which passes through the more widely open throttle valve being augmented by that which passes through the auxiliary air intake, the latter thinning the mixture in the manifold beyond the throttle valve and before it reaches the explosion chamber.

The suction on the piston from the manifold, caused by the operation of the engine, becomes effective in accordance with the opening and closing of the throttle valve, that is, the wider open the throttle valve the less suction there will be on the controller piston and the more auxiliary air and the more fuel will be supplied and the inverse of this is true in a corresponding degree on the closing movement of the throttle valve.

Upon opening the throttle valve, the main air supply, the auxiliary air supply, and the fuel supply all will be increased, so that while the engine is running the operation of the throttle will control the supply of air and gas, as the operator may deem proper to meet the requirements of the load, both air and gas being supplied in greater amount when the throttle is open and in lesser amount when the throttle is closed. It will be seen, however, that the control upon the auxiliary air and the fuel valve is exerted indirectly through the throttle and by the employment of the suction connection between the piston chamber 12 and the manifold connection at a point intermediate the throttle valve and engine.

125 By the invention, when starting the engine, I am enabled to have the fuel valve open wide at first and thereby get a rich mixture at the proper time and after starting the engine the fuel valve and the aux- 130

iliary air are controlled by the piston working automatically and the proper mixture is produced to meet the demand of the engine accordingly as the throttle is more or less opened.

- As illustrating the fact that the invention may be embodied in different forms, reference is made to Fig. 5 in which the adjustment of the fuel valve may be secured by threading the upper end of the stem and turning it by means of the finger piece 22, through the jam nut 23 which bears on the block 24 to which the lever 25 is pivotally connected at 26 at its forked end. This lever 10 is pivoted to the frame bracket or ear 27 at 28, and it is operated by the arm or lever 29, pivoted to the ear at 30 and connected to the lever 25 by an adjustable clamp pin or screw 31 which passes through a slot in both levers. 15 The lever 29 is connected with the piston pivotally at 32. By adjusting the pin or screw 31 different degrees of movement can be imparted to the lever 25 and needle valve from the movement of the lever 29. In this 25 form the needle valve passes loosely through the controller piston 19.

The controlling mechanism hereinbefore described will accommodate itself, within certain limits, to the requirements of the 30 load imposed on the engine, without alteration of the adjustment of the throttle valve, this result flowing from the fact that the suction pull through the by-pass port or conduit 21 exerted on the controller piston 35 tends to close the auxiliary air port and the fuel valve and when this suction pull is reduced the controller piston, under the action of the spring, will open more or less. Therefore, upon an increase, of the load on 40 the engine piston and its slowing down, the suction pull will be reduced on the controller piston and this will rise letting in more auxiliary air and more fuel to supply the needs of this extra load. 45 By connecting the conduit 21 with the main air inlet in advance of the fuel valve and anterior to the choke valve 3', the main air supply and the auxiliary air supply may both be simultaneously strangled thereby enabling a rich mixture to be sucked into the 50 engine for facilitating the initial starting of the latter.

I claim:—

1. In a carbureter, a fuel valve, a throttle valve, an air passage directing the air past 55 said fuel valve, an auxiliary air conduit communicating at its ends with said air passage and by-passing said fuel valve and said throttle valve, and suction controlled means acting to vary the volume of air furnished 60 by said auxiliary air conduit.

2. In a carbureter, a fuel valve, a throttle valve an air passage directing the air past said fuel valve, an auxiliary air conduit communicating at its ends with said air passage and by-passing said fuel valve and said throttle valve, suction controlled means acting to vary the volume of air furnished by 65 said auxiliary air conduit, and means for simultaneously strangling said air passage 70 and said auxiliary air conduit.

3. In a carbureter, a fuel valve, a main air passage directing the air past said fuel valve, a throttle valve, a suction connection, an auxiliary air conduit adapted to receive 75 air from said air passage and conduct the same to said suction connection between the throttle valve and the engine, suction-controlled means acting automatically to move said fuel valve to vary the quantity of fuel 80 admitted to the main air passage and concurrently and proportionately vary the volume of air furnished by the auxiliary air conduit, and a choke valve located between the intake orifice of said air passage and 85 the intake orifice of said auxiliary air conduit for simultaneously strangling said air passage and said auxiliary air conduit.

4. In a carbureter having an air inlet and an outlet adapted to be connected to the 90 manifold of an engine, a fuel valve, a throttle valve, an auxiliary air conduit connected at one end with the outlet and at its opposite end with the carbureter between the air inlet orifice and the fuel valve and by-passing the fuel valve and the throttle valve, and means in said auxiliary air conduit and controlled by the suction therein for actuating the fuel valve and controlling the auxiliary air supply. 95

In testimony whereof I affix my signature.

ADOLPH F. YOUNG.
